ATTORNEY

UNITED STATES PATENT OFFICE.

FRANK S. WOOD, OF LUMBERVILLE, PENNSYLVANIA.

MUSIC-LEAF TURNER.

1,296,725.

Specification of Letters Patent. Patented Mar. 11, 1919.

Application filed July 28, 1916. Serial No. 111,872.

To all whom it may concern:

Be it known that I, FRANK S. Wood, a citizen of the United States, residing at Lumberville, in the county of Bucks and 5 State of Pennsylvania, have invented certain new and useful Improvements in Music-Leaf Turners, of which the following is a specification.

This invention relates to music leaf turners, and the object of the same is to provide an improved means for quickly and accurately turning the pages of sheet music without tearing the same or without requiring the operator to handle the same.

15 Applicant is aware that there have been many devices for turning music invented, and the principal object of this invention is to provide a device that will accomplish the result and which is simple in construction, 20 efficient in operation and consists of the minimum number of parts.

A still further object of this invention is to provide a device as above set forth which includes a supporting frame that can be 25 folded and thus retain the music secured thereto while being transported.

With these and other objects in view, this invention consists of certain novel constructions, combinations and arrangement of 30 parts, as will be hereinafter fully described and claimed.

In the accompanying drawings:

Figure 1 is a front elevation of the improved device.

35 Fig. 2 is a section taken on line 2—2 of Fig. 1.

Fig. 3 is a view in elevation of a portion of the turning means, the tube that supports the arm of one of the turning elements being shown in section, and

40 Fig. 4 is a vertical sectional view of one of the hooks used to attach this invention to a support.

Referring to the parts by reference numbers, the device comprises a frame 10 made in two sections having lapping ears 11 on the horizontal strips thereof and brace rods 12 in connection with the frame which 45 perform the dual purpose of a support for the music. Rests for the music are designated by the numeral 13, the same being formed integrally with the lower of the horizontal strips of the frame sections. Also 50 formed integrally with the lower of the horizontal strips of the frame are rear-

wardly bent hooks 14 whose bills have covering 15 thereon so as to prevent the same from marring the music rack of the piano. The means for turning the sheets of music comprises a vertically arranged rod 16 which 60 has at its lower end a crank 17 terminating in the hand grip 18. At the opposite end thereof is the arm 19. A tube 20 is loosely carried on the rod 16 and has at its lower end a crank 21 that terminates in a hand 65 grip 22. It is to be observed that this crank 21 is spaced from the crank 17 and the grip portion 22 is so spaced from the grip 18 as to permit ready access thereto. At the upper end of the tube 20 is an arm 23 that extends 70 beneath the arm 19 and in parallelism therewith. Suitable clips 24 are loosely carried by the arms 19 and 23 and also by the uppermost of the horizontal strips of the frame 10.

75 It is to be observed that the tube 20 is journaled through the hinge ears 11 and thus forms the pintle for the said ears. With this construction the frame sections can be folded and the music retained therein while being transported. Because of the positive 80 movement given the sheets of music attached to the clips it will be only necessary to have the clips in engagement with every other sheet of music.

85 It is obvious that minor changes may be made in the form and construction of this invention without departing from the material parts thereof. It is therefore not wished to confine the invention to the exact 90 form herein shown and described, but it is wished to include all such as properly come within the scope claimed.

I claim—

95 In a music leaf turner, the combination with a two part frame, hinges connecting the parts and including a tube and a shaft extending therethrough, and a leaf-turning mechanism proper, whereof said tube and shaft are parts; of the music leaf rack along the lower bar of each part of the frame, and on each part an upstanding rearwardly bent hook provided with a soft covering adapted to engage over the music leaf rack of a piano.

100 In testimony whereof I affix my signature 105 in presence of two witnesses.

FRANK S. WOOD.
